US0D1029511S

(12) **United States Design Patent** (10) **Patent No.:** **US D1,029,511 S**
(45) **Date of Patent:** **** Jun. 4, 2024**

(54) **SEATING UNIT**

(71) Applicant: **JOHN POMP STUDIOS, INC.**,
Philadelphia, PA (US)

(72) Inventor: **John Pomputius**, Philadelphia, PA (US)

(73) Assignee: **JOHN POMP STUDIOS, INC.**,
Philadelphia, PA (US)

(**) Term: **15 Years**

(21) Appl. No.: **29/865,520**

(22) Filed: **Jul. 29, 2022**

(51) **LOC (14) Cl.** **06-01**
(52) **U.S. Cl.**
USPC **D6/335**

(58) **Field of Classification Search**

(57) **CLAIM**

The ornamental design for a seating unit, as shown and described.

DESCRIPTION

FIG. 1 is a perspective view of a first embodiment of a seating unit illustrating my new design;
FIG. 2 is front elevation of FIG. 1;
FIG. 3 is a rear elevation view of FIG. 1;
FIG. 4 is a right elevation view of FIG. 1;
FIG. 5 is a left elevation view of FIG. 1;
FIG. 6 is a top plan view of FIG. 1;
FIG. 7 is a bottom plan view of FIG. 1;
FIG. 8 is a perspective view of a second embodiment of a seating unit illustrating my new design;
FIG. 9 is front elevation of FIG. 8;
FIG. 10 is a rear elevation view of FIG. 8;
FIG. 11 is a right elevation view of FIG. 8;
FIG. 12 is a left elevation view of FIG. 8;
FIG. 13 is a top plan view of FIG. 8;
FIG. 14 is a bottom plan view of FIG. 8;
FIG. 15 is a perspective view of a third embodiment of a seating unit illustrating my new design;
FIG. 16 is front elevation of FIG. 15;
FIG. 17 is a rear elevation view of FIG. 15;
FIG. 18 is a right elevation view of FIG. 15;
FIG. 19 is a left elevation view of FIG. 15;
FIG. 20 is a top plan view of FIG. 15; and,
FIG. 21 is a bottom plan view of FIG. 15.

The broken lines in the figures depict portions of the seating unit that form no part of the claimed design.

1 Claim, 14 Drawing Sheets
